(57) **CLAIM**

The ornamental design for a dual curved support for an exercise device, as shown and described.

DESCRIPTION

FIG. 1 is a perspective view of a dual curved support for an exercise device of the present invention, with a seat assembly and portions of a support structure shown in broken, phantom lines;

FIG. 2 is a front view of the dual curved support of FIG. 1; FIG. 3 is a rear view of the dual curved support of FIG. 1; FIG. 4 is a left side view of the dual curved support of FIG. 1; FIG. 5 is a right side view of the dual curved support of FIG. 1;

FIG. 6 is a top view of the dual curved support of FIG. 1; and, FIG. 7 is a bottom view of the dual curved support of FIG. 1. The broken lines of the figures showing additional portions of the exercise device are included for the purpose of illustrating environmental structure and form no part of the claimed design.
